United States Patent Office.

J. C. SMITH, OF MAHANOY, PENNSYLVANIA.

Letters Patent No. 90,468, dated May 25, 1869.

IMPROVEMENT IN WATER-WHEELS.

The Schedule referred to in these Letters Patent and making part of the same.

To all whom it may concern:

Be it known that I, J. C. SMITH, of Mahanoy, in the county of Northumberland, and State of Pennsylvania, have invented a new and improved Water-Wheel; and I do hereby declare that the following is a full, clear, and exact description thereof, which will enable others skilled in the art to make and use the same, reference being had to the accompanying drawings, forming part of this specification.

My improved wheel is similar in its construction, and the mode of its operation, to the wheels patented by D. Andrews, Andrews and Kalbach, and Hoag and Smith, the same being dated and numbered, respectively, as follows: March 8, 1859, No. 23,144; August 30, 1859, No. 25,237, (reissued January 14, 1862); and April 1, 1862, No. 34,832.

It differs from the wheels just mentioned, as also from any other horizontal wheel with upper discharge, chiefly in the form of its buckets.

The wheel is mounted on a spiral chute, or water-way, and enclosed in a suitable casing. The water enters the wheel through the spiral water-way, and, issuing at the top of the wheel, escapes, through the space between the wheel and the casing, into the tail-race.

Figure 1 shows a bottom view of the wheel, the curves indicating the shape of the buckets at their lower ends, where the water from the spiral water-way strikes them;

Figure 2 shows a top view of the wheel, the radial lines indicating the shape of the buckets at their upper ends, where the water leaves them;

Figure 3 represents an elevation of my improved wheel, as mounted above the spiral water-way, and enclosed in the casing; and

Figure 4 represents a plan of the water-way and casing.

Similar letters of reference indicate corresponding parts.

The buckets are placed at equal distances round a circular hub, in such a manner, that the water flowing up the spiral water-way, shall strike them at right angles, or nearly so.

The bottom edges of the buckets extend from the hub in radial lines, about one-third their lengths, and then change into curves, as they approach the periphery.

This shape of the buckets at their lower ends remains nearly the same as far up as the water from the spiral chute can exert a direct action upon the buckets.

The buckets so shaped at their lower ends, offer an inclined plane, against which the water can act, not only in the direction of the wheel's motion, but also in a tangential direction, into which it is forced by its circular passage and the centrifugal force.

As there is no force by which the water is driven toward the hub, there is not only no need of any curves or inclined planes there, as are found in Andrews and Kalbach's wheel, and Hoag and Smith's wheel, but they are disadvantageous to the well-working of the wheel, inasmuch as they tend to assist the centrifugal force in driving the water from the hub toward the periphery.

The top edges of the buckets are radial lines, which are extended some distance into the thickness of the outer rim, by means of a wedge-shaped piece cut from the inner side of the rim, in a line tangential to a point on the rim some distance back from the issue-aperture.

The reason for this shape of the buckets at their upper ends is to give the water a free discharge from the wheel, to diminish friction, and to lengthen the arms of the lever, upon which the water reacts, without retarding the motion of the wheel, and thereby to give additional power to the wheel.

Having thus described my invention, I claim as new, and desire to secure by Letters Patent—

Spiral buckets, whose bottom edges extend in radial lines from the hub, about one-third their lengths, and then change into curves as they approach the periphery, and whose top edges are radial lines, the length of which exceeds the radial length of the bottom edges, in proportion to the thickness of the wedge-shaped piece cut from the inner side of the outer rim, as described.

J. C. SMITH.
